UNITED STATES PATENT OFFICE.

SAMUEL BARUCH, OF NEW YORK, N. Y.

COOLER FOR AUTOMOBILE AND OTHER RADIATORS.

1,323,813.

Specification of Letters Patent.

Patented Dec. 2, 1919.

Application filed July 22, 1918. Serial No. 246,168.

To all whom it may concern:

Be it known that I, SAMUEL BARUCH, a citizen of the United States, and a resident of New York city, borough of Manhattan, in the county of New York and State of New York, have invented a new and Improved Cooler for Automobile and other Radiators, of which the following is a full, clear, and exact description.

10 My invention has for its object to provide a neat and inexpensive cooler for automobile and other radiators, the cooler being provided with a drum with a plurality of disks with openings between which steam 15 from the radiator will be condensed, the waters of condensation flowing back to the radiator.

Additional objects of the invention will appear in the following specification in 20 which the preferred form of my invention is described.

In the drawings similar reference characters refer to similar parts in all the views, in which—

25 Figure 1 is a sectional elevation showing how my cooler is mounted on an automobile radiator.

Figs. 2 and 3 are plan views illustrating the disks; and

30 Fig. 4 is a side elevation of the nut which I employ to hold the drum on the radiator cap.

By referring to the drawings, it will be seen that the drum 5 has a head 6 which has 35 an opening 7 therein. A nipple 8 extends from the head 6 around the opening, this nipple being provided with a shoulder 9 and having a narrow thread 10 beyond the said shoulder. With this construction the 40 two portions of the nipple 8 beyond the shoulder may be disposed in an opening 11 in a radiator cap 12, and the nipple 8 at its shoulder 9 seating itself against the top of the said radiator cap. A gasket 13 is 45 then disposed around the nipple 8 and against the under side of the radiator cap 12.

The nut 14 is hollow, as is illustrated in Fig. 1 of the drawings, and is provided with orifices 15 which extend through its inner 50 and outer surfaces, so that steam from the radiator may pass through the nipple 8 to the tube 16 disposed in the drum 5. The lower end of the said tube 16 is beveled at 17 and is disposed on a seat 18 in the head 17 and is disposed on a seat 18 in the head 55 6 around the opening 7 therein. The upper

sides of the drum 5 are threaded at 19, and meshing with this thread 19 there is a thread 20 on a head 21, which closes the upper end of the drum 5. This head 21 is provided with a seat 22 in which the upper end 23^a of the tube 16 is disposed.

It will be seen that with this construction the tube 16 will be held firmly in place, although it is possible at any time to readily remove the tube 16 from the drum 5 by simply removing the head 21. Extending outwardly from the tube 16 there is a flange 23 and extending inwardly from the drum 5, adjacent its head 6, there is a shoulder or flange 24. Disposed between the said shoulder 24 and the flange 23, there are disks 25 and 26, said disks being disposed around the tube 16 and being spaced apart by collars 27.

It will be understood that the flange 23 will serve to press the disks 25 and 26 down until the lower disk is firmly seated against the shoulder or flange 24, so that there will be no danger of the disks rattling when the automobile is driven over a rough road. When necessary, in order to prevent rattling, I will construct the collars 27 of rubber or other yielding material, so that in all cases rattling will be prevented. Below the bottom disk there are openings 28 in 85 the tube 16.

In using the invention when the water in the radiator 29 becomes overheated, steam will rise and pass through the orifices 15 in the hollow nut 14, up through the nipple 90 8 and into the tube 16, passing out through the orifices 28 to the drum 5. The said steam will then flow upwardly through the orifices 26^a which are disposed at the outer sides of the disk 26 and through the orifices 95 25^a which are disposed at the inner sides of the disk 25. The steam will, therefore, flow through the orifices 26^a, then inwardly through the orifices 25^a, then outwardly through the orifices 26^a and continue in this 100 manner so that the steam will be condensed. The drum 5 together with the disks 25 and 26 will be kept cool by the rush of air against the outer surface of the drum as the automobile is driven. The waters of condensation will flow through the orifices in the disks 25 and 26, then inwardly through the orifices 28 to the tube 16, and then downwardly and out through the orifices 15 in the hollow nut 14.

Having thus described my invention, I claim as new and desire to secure by Letters Patent:

1. In a cooler for automobile and other radiators, a drum having an orifice adjacent its top, and a head at its bottom with an opening and a seat therearound, a tube in the drum seated at the seat, a head closing the top of the drum which engages the tube to close the top thereof and hold the tube on its seat, the tube being provided with an orifice adjacent its lower end communicating with the bottom of the drum around the tube and which permits steam to pass into the drum between the tube and the walls of the drum and water of condensation to flow from the bottom of the drum into and down in the tube, and disks provided with orifices spaced apart around the tube.
2. In a cooler for automobile and other radiators, a drum having heads at its top and bottom and an orifice adjacent its top, there being an opening in the head at the bottom of the drum, a tube in the drum seated around the opening, the tube being provided with an orifice adjacent its lower end communicating with the bottom of the drum around the tube and which permits steam to pass into the drum between the tube and the walls of the drum and water of condensation to flow from the bottom of the drum into and down in the tube, and disks spaced apart around the tube.
3. In a cooler for automobile and other radiators, a drum having heads at its top and bottom and an orifice adjacent its top, the head at the bottom of the drum being provided with an opening, a tube disposed in the drum and having at its lower end communication with the exterior of the drum through the opening in the head at the bottom of the drum, a plurality of disks provided with orifices spaced apart around the tube, the tube being provided with an orifice adjacent the head at the bottom of the drum and communicating with the bottom of the drum around the tube which permits steam to pass into the drum between
- the tube and the walls of the drum and water of condensation to flow from the bottom of the drum into and down in the tube.
4. In a cooler for automobile and other radiators, a drum having a head at its bottom with a depending nipple provided with a shoulder, the nipple being threaded below the shoulder, a hollow nut meshing with the thread on the nipple, the hollow nut being closed at its bottom and being provided with an opening extending through its side, a tube in the drum seated at the nipple, disks with orifices spaced apart around the tube, and a head at the top of the drum, the tube having an orifice at its lower end which permits steam to pass into the drum between the tube and the walls of the drum and water of condensation to flow from the bottom of the drum into and down in the tube.
5. In a cooler for automobile and other radiators, a drum having heads, one at its top and the other at its bottom and with an orifice adjacent its top, there being an opening in the head at the bottom of the drum with a seat therearound, there being a seat in the head at the top of the drum, a tube in the drum seated at the seats in the heads, the tube being provided with an orifice adjacent its lower end, and disks provided with orifices spaced apart around the tube.
6. In a cooler for automobile and other radiators, a vertical drum having an opening in its bottom and an orifice adjacent its top, a tube in the drum having communication beyond the drum through the opening, an inner flange in the drum, disks disposed around the tube and above each other with the lower disks resting on the flange, spacing members between the disks, an outer flange on the tube engaging the upper disk, and a head for the top of the drum for holding the tube down so that its flange will hold the disks in position, there being an opening in the tube adjacent the bottom of the drum, for the purpose specified.

SAMUEL BARUCH.
